M. J. KERMER

CRYSTALLIZER

Filed April 2, 1924

UNITED STATES PATENT OFFICE.

MARTIN J. KERMER, OF EVANSTON, ILLINOIS.

CRYSTALLIZER.

Application filed April 2, 1924. Serial No. 703,832.

To all whom it may concern:

Be it known that I, MARTIN J. KERMER, a citizen of the United States, residing at Evanston, in the county of Cook and State 5 of Illinois, have invented certain new and useful Improvements in Crystallizers, of which the following is a specification.

The invention relates to crystallizers.

One of the objects of the invention is to 10 provide a machine thru which a liquid in a condition of concentration may be passed, which will act upon the liquid to hasten the formation of crystals of a more desirable character of purity, size and abundance.

Another object is to improve machines of 15 this character.

Other objects, advantages and benefits will appear from a consideration of the following description and the accompanying drawing, forming a part hereof, wherein:—

Fig. 1 is an axial section of the device.

Fig. 2 is a horizontal elevation thereof.

Both views are broken to indicate the fact that the device may be longer than shown. 20 In both views the same reference characters indicate corresponding parts.

If some solutions, subject to crystallization, are briskly agitated and at the same time suddenly chilled, or heated, they may 25 thus be made to furnish very nearly chemically pure crystals and much larger and more abundant crystals than otherwise, and when this effect is rapidly produced the mother liquor containing the impurities may 30 be washed away. The crystallizer herein disclosed provides means whereby the solution may have its temperature quickly changed by a heating or cooling agent, and means for agitating the solution by a sort of 35 kneading process is provided effecting a continuing forward and backward movement of the solution during its progress thru the conduit, in which the extent of the forward 40 movement predominates thereby causing the solution and resulting crystals to progress slowly thru the conduit and maintaining 45 said contents in active motion.

In the drawing 5 is a head having an inlet 50 opening 6 and having a cap plate 7, for closing the head, extending into a shaft bearing 8 for the axial shaft 9. A gear wheel 10 is secured to the end of the shaft 9 and is a means thru which the shaft may be rotated. Secured to the head 5, a flanged

sleeve 11 is provided with an opening 12 55 thru which a temperature changing agent passes into the outer conduit. Chamber 14 is provided between the outer conduit pipe or cylinder 13 and the concentric inner pipe or cylinder 15. The conduit pipe 15 encloses a conduit chamber 16 to contain material to be acted upon.

On the shaft 9 is a spiral conveyor 17 of the worm type, which will move the material from the head 5 to the discharge end 65 of the crystallizer.

Another conveyor 18 which consists, as shown, of a series of spaced blades, mounted on the same shaft 9 and turning therewith but which are disposed at a different angle 70 to the shaft from that of the blades 17 and which will move the material or parts thereof in an opposite direction, so that there is a kneading action by the fore and aft movement of the material effected by the 75 two conveyors during its transit thru the machine.

The material will be finally moved entirely through the interior conduit because the rearward or return movement is not so great 80 as the initial forward movement owing to the difference in the moving ability of the two conveyors. The conveyor 17 pitched in a direction will move the material a further distance than the conveyor 18 which is 85 pitched in an opposite direction.

The shaft 9 requires bearing supports at frequent intervals and the cylinder 13 should be provided with expansion joints so as to compensate for the difference in expansion 90 and contraction of the cylinders 13 and 15. To this end a cylinder 20 is provided having a gland 19 at each end to compress and hold a packing ring 21 in place. The glands each have an annular flange 22. The cylinder 20 has a cooperating flange 23 at each of its ends, and bolts 24 pass thru the flanges to force the gland in place. The intention and object of this section is to provide means for supporting a shaft bearing as 100 well as operating as an expansion joint member.

A shaft bearing 25 has two hubs. The hub 26 provides the bearing for the shaft 9 and the hub 27 is screw threaded to receive 105 adjacent threaded ends of pipes or cylinders 15, the remaining ends of the pipes or cylinders 15 are screwed into flange coupling

members 11—11, and these flanges may be attached to sections similar to those just described until the crystallizer has been made the desired length.

5 While I have described the device by referring to it as a crystallizer, it is obviously clear that it may have many other uses, the word crystallizer being employed for the purpose of definition and not as a limitation.

10 The bearing member 25 may be an integral part of the cylinder 20 or it may be a separate part fitting closely within the cylinder and removable therefrom. It supports both conveyors, the shaft and the cylinders 15—15, within the outer cylinders 13 and 20.

15 The cylinders of the crystallizer may be made by using standard pipes and its linear dimensions may be prolonged to any desired extent by additional units, substantially such as described.

20 Means for exhausting the inner conduit 16 of vapor may be connected to opening 6 or elsewhere. The speed of the conveyor may be adjusted to correspond with the character of material being treated.

25 Having described my invention what I claim as new and desire to secure by Letters Patent, is:—

30 1. A crystallizer comprising two concentric conduits, the outer conduit to contain a temperature changing agent and the inner conduit to contain material to be acted upon; a conveyor within the inner conduit to move a portion of said material in a given direction thru the conduit; another conveyor 35 to move a portion of said material to a less extent in an opposite direction; an axially positioned shaft comprising a part of both conveyors and bearings for the shaft 40 at intervals within the inner conduit.

45 2. A crystallizer comprising two concentric conduits, the outer conduit to contain a temperature changing agent and the inner conduit to contain material to be acted upon; a conveyor within the inner conduit to move a portion of said material in a given direction thru the conduit; another conveyor to move a portion of said material to a less extent in an opposite direction; an 50 axially positioned shaft comprising a part of both conveyors; a shaft bearing supported

by the outer conduit said bearing having a passageway to connect sections of the outer conduit.

3. A crystallizer comprising two concentric conduits; an axially positioned shaft in the inner conduit comprising part of a conveyor; a conduit section in the outer conduit having an expansion joint connection with an adjacent section of the outer conduit and a shaft bearing carried by the first mentioned section.

4. A crystallizer comprising two concentric pipes, the inner pipe for conducting material to be acted upon and the outer pipe 65 to conduct a temperature changing agent; an agitating conveyor in the inner pipe to move material therethrough; a shaft in the inner pipe to drive the conveyor; a bearing member supported by the outer pipe, 70 having two concentric hubs, one in the inner pipe to afford bearing support for said shaft and one in the outer pipe to which adjacent sections of the inner pipe are connected said structure having a passageway 75 between said hubs.

5. A crystallizer comprising two concentric pipes, the inner pipe to contain material to be acted upon and outer pipe to contain a temperature-changing agent; a 80 screw conduit in the inner section comprising a shaft and a series of separated spirally inclined blades to move material in a given direction thru said pipe and alternating blades inclined in an opposite direction 85 to move said material in an opposite direction to produce a kneading action, said blades mounted on said shaft; a shaft bearing structure supported in the outer pipe having a shaft bearing in the inner pipe 90 and having a passageway in each pipe.

6. A double conduit comprising two concentric pipes; a shaft in the inner pipe; a conveyor means mounted on the shaft; a shaft bearing structure having two concentric hubs, one to afford bearing for the shaft and the other into which the inner pipe is secured and a by-pass thru said structure in each pipe.

95 In testimony whereof I hereunto set my hand.

MARTIN J. KERMER.
